FUEL INJECTOR

Louis O. French, Milwaukee, Wis.

Application October 23, 1943, Serial No. 507,362

7 Claims. (Cl. 299—107.5)

The invention relates to fuel injectors for internal combustion engines.

Directional spray nozzles are usually of the open type with the spray passages at some distance from the control valve or are of the closed type having needle type valves opening opposite to the direction of fuel flow. The first of these is objectionable because of the drop in pressure occurring between the control valve and the spray passages and the inaccessibility of the supply ends of these passages and the second because of the relatively high cost of the needle type valve and the sealing of the spray passages by a valve area greater than a line contact. Both forms also usually have dead end portions at the end of a long small passage which allow fuel deposits to build up and interfere with the proper spraying of the charges. One object of this invention is to overcome the above objections by providing a directional spray valve with control valve opening in the direction of fuel flow which may be relatively cheaply made as it requires no stem seal and in which the nozzle forms a stop for the valve and has the spray passages arranged immediately adjacent but outside of the seat of the valve and which because of the arrangement of the parts may be readily cleaned, said nozzle also preferably having a bottom opening to permit flushing of the space adjacent the directional spray passages to cool the valve and nozzle and prevent deposits of carbonized fuel that might interfere with the movement of the valve.

A further object of the invention is to provide a spray valve which may be readily cooled if desired.

The invention further consists in the several features hereinafter set forth and more particularly defined by claims at the conclusion hereof.

In the drawing:

Fig. 1 is an enlarged vertical sectional view through a fuel injector valve embodying the invention;

Fig. 2 is an enlarged view similar to Fig. 1 showing certain modifications.

In the drawing, the numeral 3 designates a nozzle member, 4 a control valve, 5 a valve seat member, 6 a casing member, 7 a flanged nut for clamping the nozzle assembly against a pipe member of a separate pump system or the pump barrel 8 of a unit injector. The parts 5 and 6 form a valve housing.

The valve seat member 5 has a cylindrical extension 9 centering it in a centrally disposed fuel supply bore 10 in the casing 6 and a shoulder

11 which abuts in fluid-tight engagement with the reduced inner end of said casing. The member 5 has a centrally disposed valve guide bore 12, a seat 13 at the inner end of said bore and a surface 14 tapering from the seat to said shoulder 11, the included angle of the sides of said surface being preferably about sixty degrees. The sloping of this surface facilitates the placing of the spray passages close to the valve seat.

The valve 4 has a stem slidably mounted in the bore 12 and a head held against the seat 13 preferably by a tension spring 15 whose lower hooked end extends through a hole 16 in the valve stem and whose outer eyed end is anchored to the casing 6 by a pin 17 that at its outer ends rests on an annular surface formed by a counter-bore 18 at the outer end of the bore 10 in said casing.

The head of the valve 4 tapers to a point 19 whose tapered surface is coaxial and co-angular with the surface 14.

The nozzle member 3 has a bore 20 to receive the reduced portion of the casing 6 and a tapered bore 21 extending from said bore 20 and co-tapered with the taper of the surface 14 to provide a fluid seal therebetween and which in Fig. 1 extends to the tip. The head of the valve is spaced a short distance from the nozzle to provide a small lift, for example, from ten to thirty-thousandths of an inch. This clearance space may be obtained by making the diameter of the base of the point 19 slightly less than the outer diameter of the valve seat.

Directional spray openings 22 are formed in the nozzle member 3 in line with or closely adjacent the valve seat back of the head of the valve in its open position. An opening 23 is also preferably provided at the bottom end of the bore 21.

With this construction when the fuel pressure acting on the valve 4 overcomes the tension of the spring 15, the valve opens outwardly until its head strikes the end of the nozzle 3. During the time the valve moves to its stop position some fuel will pass between the valve and the lower end of the nozzle and be sprayed out through the opening 23, and also during this time and while the valve is in its open position, fuel will also pass through the spray openings 22 into the cylinder of the engine, these spray openings being disposed at the desired angle relative to the head and piston of the engine to project the fuel into the desired locality of the combustion chamber and being circumferentially disposed relative to each other to distribute the charge throughout the air in the combustion chamber, the position

of the openings 22 varying with the type of engine and the position of the injector relative to the combustion chamber.

When the opening 23 is used, fuel passing to this opening during the time the valve is moving to open position will flush over and thus act to cool the head of the valve and the parts of the nozzle adjacent thereto, and passage of fuel through this opening will also prevent carbonized fuel depositing in the end of said nozzle member and interfering with the movement of the valve. In full open position the valve head engages the bore 21 and fuel flows only through the openings 22.

The construction shown in Fig. 2 is generally similar to that just described except that the casing member 24 and the nozzle member 25 are arranged to provide a cooling fluid chamber 26 between them and a pin 27 on the point 28 of the valve 29 is adapted to project down into the opening 30 to form a pintle-type nozzle and an annular spray during the time said valve 29 moves from its closed to its open position.

For forming the chamber 26 I provide the casing 24 with an annular recess 32, and the lower flange portion 33 is radially notched or splined at spaced intervals as indicated at 34 to allow the cooling liquid to contact the lower portion of the seat member 35 though allowing the unnotched portions of said flange to act as a guide for the bore 25' of the nozzle member 25. The outer edge 36 of the nozzle member 25 is conically inclined, and the lower spaced side 37 of the flange 38 of the casing 24 is similarly inclined to receive a packing 39' of lead, neoprene, graphite impregnated asbestos cord or other suitable material which may be distorted when the nozzle 25 is drawn up against the seat member 35 by the nut 39 to prevent leakage of cooling fluid from between these members.

Cooling fluid is led into the chamber 26 through a passage 40 and conducted away by a passage 41, both passages being formed in the casing member 24. In the case of a unit injector the passage 40 connects with the passage 42 supplying the inlet port 43 of the injection pump and the passage 41 connects with a passage 44 in the pump barrel 45, suitable means being provided to position these passages in alignment.

The clearance determining the lift of the valve 29 is shown as provided by a tapered bore 46 which is longitudinally displaced a short distance from the coaxial and cotapered bore 47, thus permitting the valve to open the amount of this displacement. This displacement of the head-engaging bore may also be used in conjunction with a valve head of smaller diameter than the seat to provide the valve lift distance.

As in the first construction, the valve 29 is held in a normally closed position by a tension spring 48 which is anchored at one end to the upper end of the valve stem and at its other end receives a pin 49 which seats at its ends on the counterbore 50 in the casing 24. The nozzle member 25 has the spray openings 51 communicating with the bore 46 adjacent the seat of the valve seat member 35 and through which the fuel issues when the valve 29 engages the bore 46 in its open position.

The operation of this injector valve is the same as the first form except that the pin 27 moves into the hole or opening 30 during the operation of the valve and the fuel from the supply pump is continually circulated through the chamber 26 to aid in cooling the nozzle in addition to the

usual cooling of the nozzle casing by parts of the cylinder head.

By the term outwardly opening valve I mean a valve which opens in the direction of fuel flow or toward the space into which the fuel is injected.

I desire it to be understood that this invention is not to be limited to any particular form or arrangement of parts except in so far as such limitations are included in the claims.

What I claim as my invention is:

1. In a fuel nozzle, the combination of a valve housing having a seat and a conically tapered surface extending back from said seat, an outwardly opening fluid pressure operated valve seated on said seat and having a head coaxial and of similar taper to said surface, a spring to hold said valve in normally closed position, a nozzle member having a tapered surface fitting said first named conically tapered surface and having a conically tapered surface portion similar to that of said valve head and engaged thereby in the open position of said valve and provided with spray openings adjacent the outer edge of said seat and back of the head of said valve when the valve is in its open position.

2. In a fuel nozzle, the combination of a pair of concentric interfitting sleeves having a cooling space formed between them, a seat member in fluid tight engagement with the lower end portions of said sleeves, the outer of said sleeves having an end forming a nozzle tip, an outwardly opening fluid pressure operated valve seated on said seat member and having a head engageable with said tip when the valve is in its open position, said tip having spray openings adjacent the seat for the valve and back of said head when the valve is in its open position, means sealing the upper ends of said sleeves from the escape of cooling fluid, and means for circulating cooling fluid through said cooling space.

3. In a fuel injector, the combination of a valve housing having a fuel passage and a seat, an outwardly opening fluid pressure controlled valve normally seated on said seat, a nozzle member having a wall portion forming a stop engaging the head of said valve when said valve is in its open position to limit the lift of the valve to not more than a thirty-thousandths of an inch and having spray passages in said wall portion whose inlets communicate with the space formed between the seat for the valve and seating surface of the valve when the valve is in its open position and are so close to said seat that the distance from the seat that the fuel travels before entering said spray passages is not more than the lift of the valve.

4. In a fuel injector, the combination of a valve housing having a fuel passage and a seat, an outwardly opening fluid pressure controlled valve normally seated on said seat and having a seating surface and a tapered head projecting beyond said seating surface, means to hold said valve in normally closed position, a nozzle member having a tapered bore portion coaxial with the head of said valve and of similar taper and whose side walls are in sealing engagement with the head of the valve when the valve is in its open position and provided with spray openings leading from said bore portion adjacent the outer edge of said seat and whose inlets are spaced from said seat a distance not greater than the lift of the valve when the valve is in its open position.

5. In a fuel injector, the combination of a

valve housing having a fuel passage and a seat, an outwardly opening fluid pressure controlled valve normally seated on said seat, a nozzle member having a wall portion forming a stop spaced a short distance from the valve in its closed position and engaging the outer end of the valve when said valve is in its open position and having spray passages in said wall portion adjacent the outer edge of said seat, the distance of the inlets of said spray passages from said seat being not greater than the lift of the valve.

6. In a fuel injector, the combination of a valve housing having a fuel passage and a seat, an outwardly opening fluid pressure controlled valve having a seat portion normally seated on said seat and a head portion projecting beyond said seat portion, a nozzle member having a bore into which said valve head projects and from which it is spaced a short distance in the closed position of the valve and by which the opening movement of the valve is limited, said nozzle member having spray passages leading from said bore adjacent the outer edge of said seat and whose inlets are spaced from said seat a distance not greater than the lift of the valve, the walls

5 of said bore beyond said spray passages having sealing engagement with said head when the valve is in its open position to confine the fuel flow from the seat opening to said spray passages to the small clearance area then existing above the seat portion of the valve.

7. In a fuel injector, the combination of a valve housing having a fuel passage and a seat, an outwardly opening fluid pressure controlled valve 10 normally seated on said seat, a nozzle member having spray openings adjacent said seat and back of the head of the valve in its open position and having a part spaced from the head of the valve in its closed position and engaging the head 15 of the valve to prevent fuel passing around said head in the open position of the valve and provided with a spray passage communicating with said seat through the space between said part and head of valve and disposed beyond said part and through which fuel may flow during the 20 opening of the valve and be cut off from said seat by said part engaging said head in the full open position of said valve.
